UNITED STATES PATENT OFFICE.

RICHARD M. TAYLOR, OF CHICAGO, ILLINOIS.

RAILWAY RERAILING-FROG.

1,194,257.

Specification of Letters Patent.

Patented Aug. 8, 1916.

Application filed May 19, 1913. Serial No. 768,653.

To all whom it may concern:

Be it known that I, RICHARD M. TAYLOR, a citizen of the United States, residing at Chicago, in the county of Cook and State of Illinois, have invented a new and useful Railway Rerailing-Frog, of which the following is a specification.

The present invention relates to improvements in rerailing frogs.

10 In carrying out my invention it is my purpose to provide an inner and an outer frog whereby the wheels of a derailed car may be easily and quickly guided to properly position the same upon the rails of the track.

15 A further object of the invention is to provide frogs for this purpose which shall be of an extremely simple construction, easily applied to the rails of the track or removed therefrom, which shall be comparatively 20 cheap to manufacture and which will adequately perform the functions for which they are devised.

With the above and other objects in view, the improvement resides in the construction, 25 combination and arrangement of parts set forth in the following specification and falling within the scope of the appended claims.

In the drawings: Figure 1 is a perspective view of a frog which I employ upon the 30 outer rail of a track, Fig. 2 is a bottom plan view of the same, Fig. 3 is a top plan view of the same, Fig. 4 is a side elevation of the same, Fig. 5 is a view of the rail engaging bolt, Fig. 6 is an end view of the frog, Fig. 7 is a perspective view of the inner frog member, Fig. 8 is a side elevation of the same, Fig. 9 is a top plan view of the same, Fig. 10 is a bottom plan view of the same, Fig. 11 is a sectional view approximately on the line 35 11—11 of Fig. 8, Fig. 12 is a sectional view approximately on the line 12—12 of Fig. 8, Fig. 13 is a plan view of the switch member, Fig. 14 is a view of the rail securing bolt, Fig. 15 is a perspective view illustrating the 40 application of the frogs.

Referring now to the drawings in detail, and especially to the outer frog, illustrated in Figs. 1 to 5 as well as in Fig. 15, the frog A comprises an elongated body member, 45 preferably formed or molded of metal. The top face of the body, for the major portion of its length is beveled upwardly, as at 1, the said beveled portion terminating in a substantially horizontally straight face 2, the 50 straight portion 2 or what may be termed

the platform, having its sides diverging in opposite directions from its juncture with the inclined portion 1, as indicated by the numerals 3, and the rear and widened end of the platform 2 is preferably rounded downwardly, as at 3'. Integrally formed with the beveled or inclined sides of the body 2 and terminating approximately at the juncture of the platform with the inclined plane 1, are longitudinally extending ribs B—B, 60 and the upper faces of said ribs are channeled, as at G, so that the outer walls of said ribs are disposed in spaced relation to the sides 3 of the platform 2. The frog A, below the rear rounded end 3' of the platform 2 is formed, upon its opposite sides, with longitudinally disposed grooves or channels 4, the walls provided by the said grooves coinciding to the cross sectional contour of the head of the rail R upon one of 70 the sides of said rail, while the straight faces C of the member A below the groove are adapted to contact with the web of said rail R, and the underfaces or base of said body A are beveled inwardly, as at 5, one of said 75 beveled walls resting upon the base flange of the rail. The walls of the platform projecting over the channels 4 are of a width equaling only the width of the head of the rail, and thus it will be noted that when 80 the frog is arranged on the rail the wheels of the rolling stock will be guided over one of the edges of the frog and forced through the groove G between the side of the platform 2 and the rib 3, and that the rim of said 85 wheel will be properly positioned upon the side of the head of the rail and the tread of the wheel will properly rest upon the head of the rail. In order to sustain the frog upon 90 the rail, the rear and widened portion of the platform directly above the channels 4 is formed with a transverse opening to receive the shank of a bolt D, the said bolt having one of its ends hooked, as at 6, to engage the 95 outer face of the head of the rail, while 100 a nut E is screwed upon the threaded end of said bolt to adjustably sustain the said bolt upon the frog.

The inner frog, illustrated in the remaining figures of the drawings as well as in the 105 mentioned Fig. 15 includes a body member H having its upper face inclined from one of its ends, as indicated by the characters I, the said inclined face terminating in a horizontally straight face which may be 110

termed a platform and which is indicated by the numeral 7. The inclined face I is centrally provided with a wheel groove N which is continued at opposite inclinations 5 over the platform, finding an outlet at the widened end of the said platform, as indicated by the characters N'. The rear portion of the platform between the diverging channels has its inner and reduced portion 10 rounded, as at 8, to receive the butt and rounded end 9 of a substantially V-shaped switch member 10. This switch may be swung toward either of the diverging portions of the channel N to close one of said 15 portions and open the other, so that the flange of the wheel, received within the said channel may be directed to either side of the frog. The rear and widened end of the frog is provided upon its sides and at the 20 channelled ends N' with longitudinally extending shoulders I' providing the top of outwardly extending portions J, the said portions J terminating in angular base portions 11, the angular portions 11 resting 25 upon the base flanges of a rail, and the portions J contact with the web of the rail, the head of the rail being received upon the shoulder I'. A bolt member L having a hooked end 12 passes through a suitable 30 opening in the frog above the shoulders I and below the inner curved end 14 of the platform of the frog, a nut M engaging with the threaded end of the said bolt for adjustably securing the bolt upon the frog 35 and forcing the hooked end 12 of the bolt into engagement with the head of the rail.

In Fig. 15 I have illustrated the members in applied position upon the rails R—R', and it will be apparent that a derailed car 40 will have the rim of one of its wheels travel within the groove N of the inner frog H being directed by the switch member 10 to its proper position upon the rail R', and likewise the opposite wheel of the truck when 45 arranged upon the frog A will be directed upon the rail R, as previously described.

From the above description, taken in connection with the accompanying drawings, the simplicity of the device, as well as the 50 advantages thereof will, it is thought, be perfectly apparent to those skilled in the art to which such invention appertains without further detailed description.

Having thus described the invention, what I claim is:

1. A rerailing frog comprising a body portion having an inclined upper surface terminating in a substantially horizontal straight platform, the said platform having its end round and the sides of the frog being formed with rail receiving pockets, a bolt having one of its ends provided with a rail engaging hook adjustable upon the frog, and the said frog having side members spaced from the inclined plane and platform and integrally formed therewith to provide side ribs for the frog. 55

2. The herein described car rerailer including an inner and an outer frog, said frogs each having their ends provided with 60 pockets to receive the heads of the rail and their underfaces flanged to contact with the webs of the rails, adjustable rail head engaging hooks upon each of the said frogs, each of said frogs including an inclined 65 plane which terminates in a substantially horizontally disposed platform, the rear of the platform being rounded downwardly, and each of said frogs having side ribs providing guides for the wheels of a truck. 80

3. The herein described car rerailer including an inner and an outer frog member, each of the frogs including a horizontally straight platform portion and an inclined plane leading from said platform, the sides 85 of the platform being formed with rail head receiving pockets and with outwardly extending portions to be received in the fishing spaces of the rails, the underfaces of the frogs being inclined from their sides to 90 their center to engage with the base flange of the rail, a transversely disposed adjustable hook member at the platform of each of the frogs to engage with the heads of the rails, the said platforms being formed with 95 oppositely diverging grooves for the rims of the wheels of the rolling stock, the said grooves communicating with the inclined planes of the said frogs, and one of the frogs at the said grooved portion thereof 100 being provided with a pivoted switch.

RICHARD M. TAYLOR.
